CLAIM

The ornamental design for a parabolic LED lamp, as shown and described.

DESCRIPTION

FIG. 1 is a front elevation view of a parabolic LED lamp showing our new design.

FIG. 2 is a rear elevation view of FIG. 1.

FIG. 3 is a top plan view of FIG. 1.

FIG. 4 is a bottom plan view of FIG. 1.

FIG. 5 is a left elevation view of FIG. 1.

FIG. 6 is a right elevation view of FIG. 1; and,

FIG. 7 is an illustrative cross sectional view of FIG. 1 of the parabolic LED lamp, illustrating the present invention. The drawings, the broken lines depict unclaimed environmental subject matter and form no part of the claim. There is no claim to the internal portions of the LED lamp. There is no claim to the cross-sectional aspects of the illustration in FIG. 7 which is provided as an illustration aid. There is no claim to the internal surfaces of the LED lamp, or portions of the design not illustrated. The LED lamp is concentric about a central axis. The lens cover is formed with a smooth surface and thereunder with the pattern noted in FIG. 3.
